SAFETY RAZOR

Filed Feb. 2, 1925

BY

A. J. C. Egberts.
J. O. Fowler
ATTORNEY

INVENTOR

UNITED STATES PATENT OFFICE.

ANTHONY J. C. EGBERTS, OF CHICAGO, ILLINOIS.

SAFETY RAZOR.

Application filed February 2, 1925. Serial No. 6,493.

This invention relates to cutting implements and in particular to sharp-edged instruments designed and used for shaving the face or head, and in which devices are employed for preventing the cutting of the skin and in which a detachable blade may be also adjusted both forwardly and rearwardly as well as in angular relation. After having been adjusted the blade may 10 be rigidly held in a detachable relation.

By my invention a handy, serviceable safety-razor is provided which is simple in construction, inexpensive to manufacture and efficient and reliable as well as durable 15 in practical use.

With these objects, and other objects and purposes which will be hereinafter described, in view, the invention consists in the construction, arrangement, combination and operation of parts set forth below.

In the drawings, illustrative of one embodiment of the invention, which accompany and form a part of this specification—

Figure 1 represents a plan view of an article constructed according to my invention;

Figure 2 is a view in section of my blade holding mechanism;

Figure 3 is a rear view of my safety razor; and

Figures 4, 5, 6, 7, 8 and 9 are elevations of blades adapted to be used with my blade holder.

The body of my safety razor comprises generally speaking the following elements:—

The numeral 1 denotes an upper plate or properly a blade carrying plate, while numeral 2 designates a lower semi-circular plate preferably extending downwardly at an angle to the first plate.

For clearness of illustration I have shown these parts as being made of separate pieces suitably held together by an intermediate and preferably integral part, but the structure may be varied so long as the functions

of the various elements are preserved, and for the purposes of this invention, the said parts may be considered as being made either structurally independent or as being unitary in form. This remark also applies to the construction of other features of this invention.

The upper plate 1 is preferably made to carry a forwardly projecting portion which I call a hood 30 or pocket, the same ordinarily being made with side walls, said hood ex-

tending forwardly from the upper thickened portion 31 of plate 1 and being preferably made in one piece with the said upper thickened portion. The latter is also preferably made in one piece with the lower 60 thickened portion 32 in such a way that the upper thickened part 31 extends above, and the lower thickened portion 32 extends below the plate 1 at a right angle thereto.

The plate 1 has two longitudinal guides 65 formed by the side edges of the same being lapped over toward each other to prevent lateral movement of the blade, which plate has an open central portion 35 which extends rearwardly to the thickened portions 31 and 32 and at its front edge the said plate is equipped with the ordinary guard fingers 5 having a dip and being curved at the ends thereof.

A bore 6 extends through the parts 31—32 75 which latter have a recess 33 at the end of the bore adjacent to the rear of the blade, in which bore a screw 20 works, a flange 21 of which is enclosed in said recess. The opposite end of the swivelled screw 20 is 80 threaded and is provided with a screw-head 3 the base of which slightly overlaps the entrance of the bore 6, thus making the base of the screw-head function as an upper collar or flange co-acting with the flange 21. 85

The thickened part 31—32 is bored diagonally at 7 which threaded bore enters the part 31 near the upper edge and corner thereof. The said bore is slanted downwardly and inwardly to accommodate a 90 plain screw 8 which screw after leaving the bore continues its downwardly and inwardly slanting direction in order to press on the flat surface of the blade at 9.

The lower forward side portions of the 95 plate 1 are preferably reinforced as at 34 so as to hold screws 10 which are constructed and arranged to pass at an angle through threaded orifices in the said plate and to extend through perforations 11 in the said 100 guides and also to engage the retaining devices at the side edges of said blades.

My razor is designed to provide for the adjustment of the blade by a longitudinal movement of the same on the body of the 105 holder, to prevent by the use of retaining means and detents any undue forward movement thereof, to rigidly maintain the blade in the forward adjusted position and to keep the blade from any lateral movement 110

thereof, and to hold the same rigidly against the razor body during the operation of shaving.

On account of the handle of the razor being adapted to be held at various angles to the body thereof it is necessary to provide positive means to prevent any lateral displacement of the blade at the time the strain or stress, occasioned by the said angular position of the handle, occurs.

I accomplish these results by the employment of the following mechanism, namely:—

I preferably use blades 12 made with a thickened rear part 13 and also provided with lateral abutments or retaining devices as for example recesses 14, shoulders 15 and 17, rectangular slots 16 or curved slots 18, although, if desired, in some cases the blades 20 may be constructed with straight side edges as shown in Figure 9.

I prefer to use blades 12 not only made with a thickened rear part 13 but also provided with a threaded orifice 19 at its rear edge in which a screw 20 may work, the annular flange 21 of which may rest in the recess 33.

It is obvious that if the bore 6 and the screw body 20 between the flange 21 and the detachable screw head 3 were not threaded said screw body 20 would turn around in the bore 6 without any forward movement; whereas the lower or outer part of the screw outward of the flange 21 being threaded it will engage the blade orifice 19, and by thus turning the screw body the blade may be advanced in position or moved rearwardly in the guides 4 according to the adjustment desired. In some cases however it may be preferable that the blade shall be moved to such a position that the detents, as screws 10, shall rest against the inner abutments formed by the retaining devices 14, 15, 16, 17 and 18 thereby preventing any farther or undue forward movement of the blade.

If now the screw 8 is manipulated said screw will by its contact with the blade at 9 force the blade downwardly and rigidly against the outer edges of the plate 1 and prevent any upward movement of the said blade.

It can be readily understood that if the orifice 19 were to be closed the screw 20 could be made to work back and forth in the bore 6 in which case the screw would merely press the blade in a forward direction, and that where such a movement alone is desired it would be possible to accomplish this by threading the flange 21 using a widened threaded recess 33, or as an equivalent means by simply closing up orifice 19 or omitting orifice 19, omitting also the flange 21 and recess 33 and by threading bore 6 and the whole length of the screw 20.

The plate 2 is preferably made with an

upturned semi-circular rim 22 and a series of engaging devices 23 on the lower face of said plate, said engaging devices in the present instance consisting of corrugations. A laterally adjustable handle-support 24 is preferably pivoted at 25 to the plate 2 and carries an overhanging lip 26 engaging the inner and outer edge of the rim 22, the said support also bearing a screw 27 to co-act with the engaging means 23 to hold the support within its plane of operation at any angular position desired as regards the body of my razor and the cutting edge of the blade.

A handle 28 may be secured to the support 29 by any suitable means as by the screw joint 29 by which the handle may be rigidly held at different angles as respects the cutting edge of the blade.

The part of screw 20 in bore 6 may be threaded, and the base of the detachable screw head 3 slightly overlaps the entrance of bore 6 thus making said base function as an upper collar or flange coacting with flange 21. Said screw 20 upon leaving bore 6 is made square to engage the square hole of screw head 3 and may be split and bent over outwardly at the sides of said base as at 20', thus securing screw head 3 firmly to the screw 20.

I wish it to be understood that I do not desire to be limited to the particular use or the exact details of construction shown and described, for obvious modifications will occur to persons skilled in the art.

What I claim as my invention is:—

1. In a device of the class described, a blade, a holder therefor having blade guiding means, a device swivelled within the holder to directly engage and force the blade forwardly and back in said guides, and stops or detents to prevent undue movement of and to retain the blade in its forward adjusted position.

2. In a device of the class described, a blade, a holder therefor having blade guiding means, a device swivelled within the holder to directly engage and force the blade forwardly and back in the said guides, and stops or detents to prevent undue movement of and to retain the blade in its forward adjusted position and to prevent lateral movement thereof, and means to rigidly hold the blade against the holder.

3. In a device of the class described, a blade, a holder therefor having blade guiding means, and a device swivelled within the holder to directly engage and force the blade forwardly and back in the said guides.

4. In a device of the class described, a blade, a holder therefor having blade guiding means, a device swivelled within the holder to directly engage and force the blade forwardly and back in the said guides, and stops or detents to prevent undue move-

ment of and to retain the blade in its forward adjusted position, and graduated handle retaining devices carried by the holder, in combination with a handle and 5 with means whereby the handle may be engaged selectively with said graduations to support the handle in different angular positions.

5. In a device of the class described, a 10 blade, a holder therefor comprising an upper and lower portion, the lower part projecting forwardly and lying substantially horizontally under the blade and having laterally disposed retaining devices at the 15 sides thereof for the sides of the blade, and the upper portion comprising forwardly projecting means spaced from the blade throughout its entire area and extending over the rear part of the said blade.

20 6. In a device of the class described, a blade, a holder therefor comprising an upper and lower portion, the lower part projecting forwardly and lying substantially horizontally under the blade and having 25 laterally disposed retaining devices at the sides thereof for the sides of the blade, and the upper portion comprising forwardly projecting means spaced from the blade throughout its entire area and extending 30 over the rear part of the said blade, in combination with a handle and a plate also extending forwardly but downwardly and formed with sustaining means to support the handle at different angles.

35 7. In a device of the class described, a blade, a holder therefor comprising an upper and lower portion, the lower part projecting forwardly and lying substantially horizontally under the blade and having 40 laterally disposed guides, a handle, and a plate also extending forwardly but downwardly at an angle and formed with a circular flange, and with means whereby the handle may be pivoted to said plate, and 45 also with sustaining means to cooperate with said flange to support the handle at different angles to the said flange.

8. In a device of the class described, a 50 blade, a holder therefor having a thickened end portion, a blade controlling means comprising a screw in said thickened portion to engage directly with the blade and move the same forwardly, and means to keep the blade from any lateral movement comprising laterally disposed guides carried by the blade holder.

9. In a device of the class described, a 55 handle, a blade, a holder therefore having a thickened end portion, a device in the thickened end to directly engage and force the blade forwardly and rearwardly, and means to keep the blade from lateral movement comprising laterally disposed guides carried by the holder, in combination with 60 a plate extending from the holder having

means to pivot the handle thereto, and also means to guide rotary movement of said handle.

10. In a device of the class described, a 70 blade, a holder therefor, a device within the holder to force the blade forwardly means to prevent undue forward movement thereof comprising lateral retaining means on the side edges of the blade and detents on the holder to engage therewith, a handle, 75 and means on the holder to support the same.

11. In a device of the class described, a 80 blade, a holder therefor, a device in the holder to force the blade forwardly and back, and means to prevent undue forward movement thereof comprising lateral retaining means on the side edges of the blade and 85 detents on the holder to engage therewith, in combination with a handle and a plate extending from the holder having means to pivot the handle thereto, and also means to guide rotary movement of the handle.

12. In a device of the class described, a 90 blade, a holder therefor, means to position the blade on the holder, and adjustable means to hold the blade against the holder comprising a screw in the holder the end of which is adapted to press upon the top surface of the blade. 95

13. In a device of the class described, a 100 blade, a holder therefor, means to position the blade on the holder, and adjustable means to hold the blade against the holder comprising a screw in the holder the end of which is adapted to press upon the top surface of the blade, in combination with a handle and a plate extending from the holder having means to pivot the handle thereto, and also means to guide the rotary 105 movement of said handle.

14. In a device of the class described, a 110 handle, a blade, a holder therefor comprising a plate, means to prevent undue forward movement of the blade, comprising detents on the blade carrying plate engaging retaining devices on the sides of the blade, said holder also comprising a plate extending downwardly at an angle to the first plate and carrying the handle. 115

15. In a device of the class described, a 120 handle, a holder comprising a plate, a blade supported thereon, means to prevent undue forward movement thereof, said holder also comprising a plate extending downwardly below the first one at an angle thereto having a semi-circular flange and a device to engage therewith having means to support the handle movable in an angular 125 position as regards the flange.

16. In a device of the class described, a 130 blade, a holder therefor comprising a plate, means to prevent undue forward movement of the blade, comprising detents on the blade carrying plate engaging retaining de-

- 5 vices on the sides of the blade, said holder also comprising a plate extending downwardly from the first plate at an angle thereto having a semi-circular rim, and a device to engage therewith and having a handle support, means to lock said plate and support together in different angular positions, and a handle carried by said support.
- 10 17. In a device of the class described, a plate holder comprising a plate, a blade held thereby, means to prevent undue forward movement of the blade, comprising detents on the blade carrying plate engaging retaining devices on the sides of the blade, said holder also comprising a plate extending downwardly, a handle pivoted to the last named plate, and means to lock said plate and handle together in different angular positions.
- 15 18. In a device of the class described, a blade, a holder therefor comprising an upper and lower portion, the lower part projecting forwardly and lying substantially horizontally under the blade and having laterally disposed guides, and a central open portion, and the upper portion comprising forwardly projecting means to extend over the rear part of the blade, said holder also comprising a plate extending downwardly and having a semi-circular rim, and a device to engage therewith having a handle support pivoted to the plate, means to lock said plate and support together in different angular positions, and a handle carried by said support.
- 20 19. In a device of the class described, a blade, a holder therefor comprising an upper and lower thickened portion, the lower part projecting forwardly and lying substantially horizontally under the blade and the upper portion comprising forwardly projecting means spaced from the blade throughout its entire area and extending over the rear part of the blade, a plate extending at an angle from the said lower thickened portion, a handle carried thereby and means passing through the holder to move the blade.
- 25 20. In a device of the class described, a blade, a holder therefor comprising a rearwardly disposed thickened portion, the lower part thereof projecting forwardly into a blade carrying plate, said plate lying parallel under the entire blade, and means passing through the thickened portion to move the blade forwardly and backwardly, said means engaging directly with the blade.
- 30 21. In a device of the class described, a blade, a holder therefor comprising a rearwardly disposed thickened portion, the lower part thereof projecting forwardly and lying substantially horizontally under the blade, and having laterally disposed guides at the sides thereof for the sides of the blade, and means passing through the thickened portion to move the blade.
- 35 22. In a device of the class described, a blade, a holder therefor comprising a rearwardly disposed thickened portion, the lower part thereof projecting forwardly and lying substantially horizontally under the blade and having laterally disposed guides at the sides thereof for the sides of the blades, and means passing through the thickened portion to move the blade, a thereunder support plate extending at an angle from the bottom of the thickened portion, and a handle carried by the support.
- 40 23. In a device of the class described, a handle, a support therefor having a curved rim, a lip on the handle to engage said rim, means to pivot the handle and support together, the latter being provided with graduated retaining means, a blade and a holder therefor attached to the said support.
- 45 24. In a device of the class described, a handle, a support therefor having a curved rim, a lip on the handle to engage said rim, means to pivot the handle and support together, the latter being provided with graduated retaining means, means to lock the handle to the latter, a blade, and a holder therefor attached to the said support.
- 50 Signed at Chicago in the county of Cook and State of Illinois this nineteenth day of January A. D. 1925.
